Primary Examiner — Darlington Ly(74) *Attorney, Agent, or Firm* — BCF LLP(57) **CLAIM**

The ornamental design for an off-road vehicle, as shown and described.

DESCRIPTION

FIG. 1 is a right side elevation view of an off-road vehicle showing our new design;

FIG. 2 is a left side elevation view thereof;

FIG. 3 is a front elevation view thereof;

FIG. 4 is a rear elevation view thereof;

FIG. 5 is a top plan elevation view thereof;

FIG. 6 is a bottom plan elevation view thereof;

FIG. 7 is a front and right side perspective view thereof; and, FIG. 8 is a rear and left side perspective view thereof.

The broken lines in the drawings illustrate portions of the off-road vehicle that form no part of the claimed design.

1 Claim, 8 Drawing Sheets(56)
